UNITED STATES PATENT OFFICE

118,593

DESIGN FOR A BOTTLE

Ernest L. Du Pree, Douglaston, Long Island, N. Y., assignor to Schenley Distillers Corporation, New York, N. Y., a corporation of Delaware

Application October 7, 1939, Serial No. 87,569

Term of patent 14 years

To whom it may concern:

Be it known that I, Ernest L. Du Pree, a citizen of the United States, residing at 244-18 Alameda Avenue, Douglaston, Long Island, county of Queens and State of New York, have invented a new, original, and ornamental Design for a Bottle, of which the following is a specification, reference being had to the accompanying drawing, forming a part thereof.

I claim:

The ornamental design for a bottle, as shown.

ERNEST L. DU PREE.
